(57) **CLAIM**

The ornamental design for the bracelet, as shown and described.

DESCRIPTION

FIG. 1 is a perspective view of a First Embodiment of the bracelet, showing my new design;

FIG. 2 is a top plan view of the design of FIG. 1;

FIG. 3 is a bottom plan view of the design of FIG. 1;

FIG. 4 is a left side elevational view of the design of FIG. 1;

FIG. 5 is a right side elevational view of the design of FIG. 1;

FIG. 6 is a left edge elevational view of the design of FIG. 1;

FIG. 7 is a right edge elevational view of the design of FIG. 1;

FIG. 8 is a perspective view of a Second embodiment of the bracelet, showing my new design;

FIG. 9 is a top plan view of the design of FIG. 8;

FIG. 10 is a bottom plan view of the design of FIG. 8;

FIG. 11 is a left side elevational view of the design of FIG. 8;

FIG. 12 is a right side elevational view of the design of FIG. 8;

FIG. 13 is a left edge elevational view of the design of FIG. 8; and,

FIG. 14 is a right edge elevational view of the design of FIG. 8.
